UNITED STATES PATENT OFFICE.

VALENTINE B. FRANGART, OF BOUNDBROOK, NEW JERSEY.

MEASURING DEVICE.

SPECIFICATION forming part of Letters Patent No. 752,446, dated February 16, 1904.

Application filed November 8, 1903. Serial No. 179,733. (No model.)

To all whom it may concern:

Be it known that I, VALENTINE B. FRANGART, a citizen of the United States, residing in Boundbrook, New Jersey, have invented certain Improvements in Measuring Devices, of which the following is a specification.

My invention consists in certain improvements in measuring devices particularly designed for determining lengths of fabrics, such as cloth, dress-goods, ribbons, &c.

The object of the invention is to provide a device of the general character above noted which is designed to be permanently supported on a counter and by which it shall be possible to quickly and accurately measure off any desired lengths of material.

A further object of the invention is to provide a measuring device which is designed to be supported on a counter and which is so made that when not in use its horizontally-extended portions may be moved into an approximately vertical position, so as to occupy but relatively little space.

These objects I attain as hereinafter set forth, reference being had to the accompanying drawing, in which the figure is a perspective view illustrating my improved measuring device in a position ready for use and indicating in dotted lines the position of its hinged arms when moved upwardly, so as to be out of the way.

In the above drawing, A is a standard held in any desired way on or supported from a store-counter or similar structure, and there is upon the upper end of said standard a horizontally-placed cross-piece a, it being noted that a portion of said standard is preferably, although not necessarily, of a circular section.

The cross-piece a is rigidly fixed to the standard and has arms a² hinged to its ends, which in the present instance are made rectangular in section and when in a horizontal position form with the said cross-piece a single and horizontally-hung bar. The hinges a' I preferably form as part of or connected to metal end sections a³, fitted on the adjacent end portions of the cross-piece a and the arms a². At the extreme end of each arm, at the center of the cross-piece a and at points midway between these first-mentioned points, are fas-

tened metallic plates a⁴, which are preferably made of such length as to extend or project beyond the sides of the pieces upon which they are carried. Each one of said plates has on its overhanging portion a short upwardly-projecting pin a⁵, and the said pins and their supporting-plates are so arranged relatively to each other that the distances between the extreme pins is equal to some common unit of length—as, for example, a yard—while the intervening pins are placed at points between said extreme pins equal to the ordinary fractions of said unit, in the present instance being at the one-fourth, one-half, and three-fourths yard points.

Ribs or bars B are pinned to the under side of the arms a², as shown, and both of said ribs are also pinned to a cylindrical ferrule or runner b, slidably mounted upon the cylindrical portion of the standard A. When in a position with its arms extended and ready for use, said runner rests upon a shoulder formed by the end of a portion of the standard A of larger diameter than that of the remainder, so that it will be understood that the ribs B act as struts to retain the arms a² in their horizontal position without permitting undue strain to be brought upon the hinges a'. An L-shaped groove or recess b' is formed in the upper portion of the runner b, and this is designed to engage a pin b², projecting from the cylindrical portion of the standard A.

In using my improved measuring device one end of the piece of fabric or other material to be measured is engaged by the pin a⁵ at one end of the arms a², and said fabric, stretched to any desired extent, is extended parallel to the measuring-bar formed of the arms a² and the cross-piece a and is brought into engagement with the pin at the extreme end of the other arm a². If a length of more than one yard of material is desired, this latter is then folded back upon itself and brought into engagement with the first pin at the opposite end of the measuring-bar, and so on until the desired length is measured off, when such length is marked or the fabric cut while being held upon the pins.

Owing to the fact that the pins overhang the sides of the measuring-bar, the main por-

tion of the fabric measured is permitted to hang down freely out of the way, and any fractions of the main length or distance between the extreme pins are measured by bringing the fabric into engagement with the proper intermediate ones of the pins a^5 .

When it is not desired to use the measuring-bar, the runner b is moved upwardly, so that its L-shaped groove b' is brought into engagement with the pin b^2 , when a slight turn of said runner causes it to be held by the pin with the arms a^2 in an upwardly-extended position. (Indicated by the lines in the figure.)

I claim as my invention—

15 1. A measuring device consisting of a standard, a cross-bar thereon and pins projecting from said cross-bar at definite distances from one another, substantially as described.

20 2. A measuring device consisting of a standard, a cross-bar thereon, an arm or arms hinged to said cross-bar and projections from said parts carried by the standard, said projections being at definite distances from one another, substantially as described.

25 3. A measuring device consisting of a standard, a cross-bar thereon, an arm or arms hinged to said cross-bar and means for engaging fabric on said parts carried by the standard, said means being at definite distances from one another, substantially as described.

30 4. A measuring device consisting of a standard, arms movably carried by the standard, means for holding said arms in a straight line and a series of projections from said arms placed at definite distances from each other, substantially as described.

35 5. The combination of a standard, arms carried thereby and movable in a vertical plane or planes, said arms having means for indicating lengths of material to be measured, means for holding the arms in a substantially straight line and other means for retaining said arms in a position out of the straight line, substantially as described.

40 6. The combination in a measuring device of a standard, a cross-piece thereon, an arm hinged to each end of said cross-piece, a runner movable on the standard and a rib con-

necting each of said arms with the runner, 50 said arms and cross-pieces having upon them means for determining the length of material to be measured, substantially as described.

7. The combination of a standard, a measuring bar or bars carried thereon and having 55 projections at definite distances from each other, said measuring-bar being in a plurality of sections movably connected together, substantially as described.

8. The combination of a standard, a measuring bar or bars carried thereon, and projections from said bar or bars overhanging a side 60 of the same, substantially as described.

9. The combination in a measuring device of a standard, a bar or bars movably carried 65 thereon and having means for measuring lengths of material, a runner on the standard, a rod or rods extending from the runner to the movable arm or arms, with means for retaining the runner in an elevated position on 70 the standard, substantially as described.

10. The combination in a measuring device of a standard, a bar movably carried thereon having means for measuring lengths of material, a runner on the standard, a rod extending from the runner to the movable arm, with means for limiting the motion of the runner upon the standard in one direction and means retaining it in a fixed position distant from said limiting means, substantially as described. 75

11. The combination in a measuring device, of a standard, a cross-bar thereon, arms hinged to said cross-bar, a runner having in it a slot and movable on the standard, rods connecting the runner and the hinged arms and a 85 projection on the standard for engaging the slot in the runner, with means on the cross-bar and on said arms for determining the length of material to be measured, substantially as described. 90

In testimony whereof I have signed my name to this specification in the presence of two subscribing witnesses.

VALENTINE B. FRANGART.
